ATTORNEYS.

UNITED STATES PATENT OFFICE

FRANK MOSSBERG, OF ATTLEBORO, MASSACHUSETTS, ASSIGNOR TO MOSSBERG PRESSED STEEL CORPORATION, OF ATTLEBORO, MASSACHUSETTS, A CORPORATION OF MASSACHUSETTS

REEL

Application filed April 27, 1928. Serial No. 273,217.

This invention relates to a reel formed of sheet material and has for its object to provide a construction by which the heads may be readily centered with reference to the barrel and firmly secured thereto.

A further object of the invention is the provision of circularly located ears secured to or carried by the head and projecting inwardly in position to receive the barrel and engage the surface thereof and be welded thereto to secure the heads in position.

A still further object of the invention is the shearing of the ears from the stock of the heads of the reel and folding them inwardly to engage the inner surface of the barrel to centralize and position the same with reference to the head and secure them thereto by welding.

With these and other objects in view, the invention consists of certain novel features of construction, as will be more fully described, and particularly pointed out in the appended claims.

In the accompanying drawings:

Figure 1 is a side elevation of the reel partly in section.

Figure 2 is a detailed sectional view thereof showing one of the ears in position.

Figure 3 is a view similar to Figure 1 showing the welding material in place.

Figure 4 is a fragmental sectional view through the reel intermediate the ears and on line 4-4 of Figure 5.

Figure 5 is a top plan view of the head of the reel.

Figure 6 is a modification showing the ear as formed separate from the head and secured thereto by welding.

Figure 7 is a still further modification showing the ear as positioned so that its edge engages the barrel.

Figure 8 is a still further modification showing a head formed of two parts with the ear formed on the outer auxiliary part and extending through the main head to engage the barrel.

It is found in the construction of reels made of sheet metal or the like with their parts secured together by welding of advantage to provide some positioning means for

centralizing the barrel and head members, which centralizing means may also be used for attaching the heads to the barrel of the reel; and the following is a detailed description of the present embodiment of this invention and showing means by which these advantageous results may be accomplished: 55

With reference to the drawings, 10 designates a barrel which is in tubular form and made from sheet stock. At each end of this barrel there is a head 11 which has a rolled stiffening peripheral edge 12, also radially disposed stiffening ribs 13. Intermediate the stiffening ribs I form ears 15 by cutting the same from the stock of the head and folding them inwardly leaving an opening 16 through the head of the reel. The ears thus formed are located in a circle and spaced apart suitable distances and together form inwardly projecting extensions over which the barrel 10 snugly fits, and is secured as at 17 by either spot welding, arc welding or gas welding. In using either of the latter two I prefer to form a hole or opening 18 in the ear for convenience 70 through which it is more desirable to supply the welding material to secure the ear to the barrel than about the edges of the ear. By the welding of these different ears to the barrel I firmly and positively attach 75 the heads of the reel thereto in an economical and convenient manner. 80

In some cases the ears may be formed as illustrated in Figure 6 showing a separate L shaped piece 19 which is welded as at 20 85 to the head 11 and extends through an opening 21 in the head and along the inner surface of the barrel 10 and is secured thereto by welding as at 22.

In still other cases an ear 23 may be cut from the stock of the head 11 and forced inwardly slightly to form an abutment, the edge of which engages the barrel 10 as illustrated in Figure 7, and through the opening 25 in the head formed by the ear cut therefrom I position welding material 26 to firmly secure the barrel and head members together. 90

In other cases, where it is desirable to provide an auxiliary plate 27 for the purpose

of forming a flat surface for stacking the reels one upon the end of the other the auxiliary plate is positioned to lie flush with the rolled edge 12 of the main head 11 and and the ears 28 cut from the stock of the 5 head 11 are folded outwardly, as illustrated in Figure 8, to space the auxiliary plate from the head and leave an opening 29. The attaching and positioning ears 30 in this case 10 are formed from the stock of the auxiliary plate 27 by cutting the ear 30 and folding the same inwardly through the opening 29 in the main head, as illustrated in Figure 8. The two ears 28 and 30 are secured together by welding as at 31, while the ear 15 30 is secured to the barrel 10 by welding as at 32 to secure the barrel to the two-part head as described. By the term "head member" in the claims I include all of the parts 20 of which the head is constructed.

Through the center of each of the reels there is a sleeve 33 which is attached to each of the heads at its center by welding as at 34 to form an additional supporting means 25 for the reel to strengthen the same and assist in tying all of the parts together.

The foregoing description is directed solely towards the construction illustrated, but I desire it to be understood that I reserve 30 the privilege of resorting to all the mechanical changes to which the device is susceptible, the invention being defined and limited only by the terms of the appended claims.

I claim:

35 1. A reel comprising a tubular barrel having inner and outer surfaces, a head at each end thereof, positioning means at the junctures of said barrel and heads comprising a plurality of ears secured to each head and 40 projecting inwardly therefrom and each having an opening therein and engaging one of the surfaces of said barrel, securing means consisting of additional metal positioned in each of said openings welding each of said 45 ears to said barrel to secure the head thereto.

2. A reel comprising a tubular barrel, a head member at each end of the barrel, ears cut from the stock of the head members and 50 folded to extend into and engage the inner surface of the barrel, each of said ears being provided with an opening through it into which welding material is deposited for securing the heads to the barrel.

3. A reel comprising a tubular barrel having inner and outer surfaces, a head member at each end of the barrel, positioning means at the junctures of said barrel and head members comprising a plurality of ears carried by each head member and projecting 55 inwardly therefrom and engaging one of the surfaces of said barrel, each of said ears being provided with an opening through it into which welding material is deposited for securing the heads of the barrel.

60 4. A reel comprising a tubular barrel, a

head member at one end of the barrel, spaced ears struck from the stock of the head member and folded to project from the head member and engage a surface of the barrel to align the head member thereon, and welding material joining edges of said ears to the engaged surface of said barrel.

5. A reel comprising a tubular barrel, a head member at one end of the barrel, spaced ears struck from the stock of the head member and folded to project from the head member and engage a surface of the barrel to align the head member thereon, and welding material securing said ears to the engaged surface of said barrel.

6. The method of forming a metal reel, including the steps of striking spaced ear portions from head portions, positioning the heads at the ends of a tubular section with each ear portion in contact with a surface of the tubular section, and depositing welding material at junctures of said ear portions and the contiguous tubular section surface to weld said ear portions to said tubular section.

7. The method of forming a metal reel, including the steps of striking spaced ear portions having openings therethrough from head portions, positioning the heads at the ends of a tubular section with each ear portion in contact with a surface of the tubular section, and depositing welding material at junctures of said openings and the contiguous tubular section surface to weld said ear portions to said tubular section.

8. The method of forming a metal reel, including the steps of striking spaced ear portions having openings therethrough from head portions, positioning the heads at the ends of a tubular section with each ear portion in contact with the inner surface of the tubular section, and depositing welding material at junctures of said openings and the contiguous tubular section surface to weld said ear portions to said tubular section.

In testimony whereof I affix my signature.

FRANK MOSSBERG.
